CLAIM

I claim the ornamental design for a cabinet having shelves, as shown and described.

DESCRIPTION

FIG. 1 is a front right perspective view of a cabinet having shelves embodying our new design.

FIG. 2 is a front elevational view of the cabinet of FIG. 1.

FIG. 3 is a rear elevational view of the cabinet of FIG. 1.

FIG. 4 is a left side elevational view of the cabinet of FIG. 1.

FIG. 5 is a right side elevational view of the cabinet of FIG. 1.

FIG. 6 is a top plan view of the cabinet of FIG. 1, which is identical to the top plan view of the cabinet of FIG. 8.

FIG. 7 is a bottom plan view of the cabinet of FIG. 1.

FIG. 8 is a front right perspective view of an alternative embodiment of the cabinet of FIG. 1.

FIG. 9 is a front elevational view of the cabinet of FIG. 8.

FIG. 10 is a rear elevational view of the cabinet of FIG. 8.

FIG. 11 is a left side elevational view of the cabinet of FIG. 8.

FIG. 12 is a right side elevational view of the cabinet of FIG. 8; and,

FIG. 13 is a bottom plan view of the cabinet of FIG. 8.
